UNITED STATES PATENT OFFICE.

FRANK M. STOLL, OF DENVER, COLORADO, ASSIGNOR TO THE STOLL MANUFACTURING CO., A CORPORATION OF COLORADO.

TENT.

Application filed September 2, 1924. Serial No. 735,433.

To all whom it may concern:

Be it known that I, FRANK M. STOLL, a citizen of the United States of America, residing at Denver, in the county of Denver and State of Colorado, have invented certain new and useful Improvements in Tents, of which the following is a specification.

This invention relates to tents, more particularly to that type known to the trade as palmetto tents, and has for its principal object the elimination, in an efficient manner, of the usual center pole employed in this type of tent.

Another object of the invention is to construct a tent of this character which can be quickly and easily erected.

A further object of the invention is to provide a tent of this character which will be light in weight and which, when collapsed, will occupy a minimum of space. Other objects and advantages reside in the detail construction of the invention, which result in simplicity, economy, and efficiency, and which will become more apparent from the following description.

In the following detailed description of the invention reference is had to the accompanying drawing which forms a part hereof. Like numerals refer to like parts in all views of the drawing and throughout the description.

In the drawing:

Fig. 1 is a perspective view of my improved tent. In this view the canvas covering of the tent is indicated in broken line to disclose the interior construction.

Fig. 2 is a cross-section through the tent, taken on the line 2—2, Fig. 1.

Fig. 3 is a perspective detail view of the support at the peak of the tent.

Fig. 4 is a detail view showing the peak support poles folded together.

Fig. 5 is a detail view of the upper extremity of what will be designated the erecting pole.

Fig. 6 is detail view of the joint employed to connect the hip poles of the tent.

Let the numeral 10 indicate the canvas covering of the tent, which is arranged to be staked to the ground, as shown at 11, in the usual manner. The covering 10 is supported at the hips of the tent by a series of inter-connecting hip poles 12 which are carried in pockets 13 on the exterior of the

tent. As shown in Fig. 6 one extremity of each of the hip poles 12 is provided with a strap 31, the other extremity being cut away as shown at 30, so as to fit into the strap at the extremity of the adjacent hip pole. The hip poles 12 are more fully described and claimed in a co-pending application for patent bearing Serial No. 543,722, filed March 14, 1922.

The peak of the tent is supported on a pad 14 carried on a plate 15 which is in turn supported on two angularly disposed poles 16. The poles are provided at their one extremity with ferrules 27 which carry tongues 28. A pivot pin 17 passes through and secures the tongues 28 to the plate 15. Flanges 24 are formed on the plate 15 to limit the spread of the poles 16.

Metallic angle sockets 18 are affixed to the other extremities of the poles 16, the angle of the sockets corresponding to the angle between the sides and the top of the cover 10. The side poles 19 are arranged to fit within the open extremities of the angle sockets 18 and rest, at their lower extremities, in tent stretchers 9. The tent stretchers are more fully described and claimed in a co-pending application bearing Serial No. 712,681, filed May 12, 1924, and comprise a dog 32 which engages notches 33 on the tent pole and holds the pole at any desired height. The side poles 19, may, if desired, be jointed as illustrated at 20 so that they will occupy a smaller space when the tent is collapsed. Straps 21 are secured on the interior of the cover 10 at the hips of the tent and are used to secure the tent cover to the angle sockets 18.

For erecting the tent an erecting pole 22 is provided. The erecting pole 22 carries at one extremity a ferrule 29 provided with a slot 23. The pivot pin 17 on the plate 15 carries a groove 25 for engaging in the slot 23 of the erecting pole.

In erecting the tent the cover 10 is first staked at its lower four corners to the ground. The hip poles 12 are inserted in the pockets 13 and secured to each other. The erecting pole 22 is connected to the plate 15, by means of the slot 23 and pivot pin 17, and the pad 14 is placed at the peak point of the cover 10. The tent is now raised and supported by the erecting pole 22 as indicated in broken line in Fig. 2. The side poles 19 are now inserted in the

angle sockets 18, placed in their proper positions at the sides of the tent, and raised in the tent stretchers 20 until the proper tension has been placed in the tent cover 10. 5 This raising of the side poles results in raising the pivot pin 17 from the slot 23 and releasing of the erecting pole 22. The straps 21 are now secured around the side poles 19 and the tent is ready for use. The 10 erecting pole may now be used if desired as one of the awning poles for supporting an awning in front of the tent.

When collapsed the poles 16 are turned upon the pivot pin 17 so as to lie parallel 15 with each other as shown in Fig. 4. An opening 26 is placed in the plate 15 which may be used for supporting a lantern in the tent. The flanges 24, when in contact with the poles 16, act to maintain the pad 14 directly over the center or pivot point. 20

A pin 34 projects above the pad 14 and engages in an eyelet opening at the exact peak point of the tent. The pin 34 facilitates the locating of the pad 14 at the peak 25 point during the erecting operation. The pad contacts with the tent around the eyelet opening and prevents any leakage at this point.

While a specific form of the improvement 30 has been described and illustrated herein, it is desired and understood that the same may be varied, within the scope of the appended claims, without departing from the spirit of the invention.

Having thus described my invention, 35 what I claim and desire to secure by Letters Patents is:—

1. Means for supporting a tent of the type 40 having an angularly depending top and relatively steeper depending side walls comprising: poles pivoted together at the peak of said tent and extending downward at an angle substantially parallel to said top and intermediate the corners of said tent; other poles arranged to be affixed to said 45 first poles and extending downward at an angle substantially parallel to and on the center line of said side walls and a series of interconnecting poles upheld by said 50 other poles and adapted to surround said tent substantially at the intersection of the top and side walls thereof so as to support the corners of said tent.

2. A four sided tent comprising a top 55 depending from a peak; side walls depending from said top at a relatively steeper angle; top poles pivoted together at the

peak of said tent and carrying a support for said peak, said top poles extending downward at an angle substantially parallel to 60 said top and intermediate the corners of said tent; side poles detachably secured to said top poles and extending downward at an angle substantially parallel to, and along 65 the center line of, two of said side walls and means extending to each side of each of said poles for holding said tent separated at the line of intersection between said top and said side walls and supporting the remaining two side walls. 70

3. A tent comprising a top depending from a peak; side walls depending from said top at a relatively steeper angle; pockets on the exterior at each side of said tent along the line of intersection between said top and said side walls; hip poles in said 75 pockets and detachably connected to each other at the corners of said tent: top poles pivoted to each other at the peak of said tent and extending downward substantially 80 parallel to said top and side poles detachably secured to said top poles and extending downward substantially parallel to and along the center line of the side walls of said tent and means for securing said 85 pockets to said poles.

4. Means for supporting a rectangular tent of the type having an angularly depending top and relatively steeper depending side walls comprising: poles secured 90 together at the peak of said tent and extending oppositely downward substantially parallel to said top; other poles arranged to be affixed to said first poles and extending downward substantially parallel to said 95 sides, all of said poles being in a vertical plane cutting two sides of said tent intermediate the corners thereof and means upheld by said poles for supporting the four corners and other two sides of said tent. 100

5. Means for supporting a four sided hipped tent comprising a pair of substantially vertical poles adjacent to and along the vertical center line of two said sides and arranged to support the peak of said tent; a hip pole arranged horizontally across each of said vertical poles at the hip of said tent and supporting two of the tent sides and other hip poles carried by and connecting the extremities of said first hip poles and supporting the remaining two sides. 105

In testimony whereof, I affix my signature.
FRANK M. STOLL.
